FIG. 2.

Patented June 21, 1927.

1,633,496

UNITED STATES PATENT OFFICE.

CARRIE ELIZABETH RICHARDSON, OF SIMPSONVILLE, SOUTH CAROLINA.

TOY.

Application filed July 29, 1925. Serial No. 46,855.

My invention relates to improvements in toys, of that type which include a driving motor for actuating a wheel on which toy cars or seats for passengers are suspended, and it consists in the combinations, constructions and arrangements herein described and claimed.

An object of the invention is the provision of a toy of the character described having a novel means for controlling the descent of a weight which is included in the gravity motor for operating the wheel so that the wheel will be operated at a substantially uniform speed and a given downward movement of the weight will cause operation of the wheel for a relatively long time.

A further object of the invention is the provision of a toy of the character described which is simple in construction and can be made at a relatively low cost of materials which are available in practically all households.

Other objects and advantages of the invention will be apparent from the following description, considered in conjunction with the accompanying drawings, in which

Figure 1 is a side elevation of the toy.

Figure 2 is a fragmentary perspective view of the toy.

Figure 3 comprises a side elevation and an edge view, respectively, of the carrying wheel of the toy.

Figure 4 is a plan view of a blank of which a car and representations of the passengers of the car are formed.

Figure 5 is a fragmentary view, showing in elevation a portion of a support for the axle of the toy, the latter being shown in section together with a fragmentary portion of a cable for turning the axle.

The supporting structure of the toy comprises a box-like lower or base section 1 which may include a removable lid 2. An upper box-like section 3 is superimposed on the lid 2 of the base section and has an opening 4 in its bottom in register with an opening 5 in the lid of the base section. The upper section 3 is open at its upper end.

Two parallel supporting plates 6 have the lower end portions thereof secured by glue or in any other suitable known manner to the upper end portions of two opposite vertical walls of the upper section 3 of the supporting structure of the toy. These supporting plates 6 extend in parallel relation above the level of the upper end of the upper section 3

and may decrease in width from the level of the upper end of the upper section 3 to their upper ends. The upper end portions of the supporting plates 6 are formed with horizontally aligned openings which constitute bearings for the end portions of a horizontal axle or shaft 7.

A wheel which is rotatably supported by the axle between the supporting plates 6 may comprise a pair of end members 8 and a sleeve or hub 9 to which the central portions of the end members 8 are joined in any suitable known manner, as by means of glue or paste. Each of the end members 8 is of circular configuration and is provided with a central opening, as at 10, (see Fig. 3). The central opening 10 of each end member 8 is in axial alinement with the bore of the sleeve 9 and the axle 7 extends through the openings 10 in the end members 8 and through the bore of the sleeve or hub 9. The axle 7 is prevented from moving axially in the openings in the supporting plates 6 in any suitable known manner, as by means of convolutions of cord on the extreme end portions of the axle, as at 11.

Each end member 8 of the wheel may have apertures in the web portion thereof spaced regularly about the center of the end member, thus producing radial spoke portions as indicated at 12 and a rim portion indicated at 13.

The rim portions of the two end members 8 of the wheel are formed with aligned openings which preferably are located in the rim portions of the end members 8 at the junctures of the rim portions with the spoke portions of said end members, as indicated at 14. Cross supporting rods 15 have the end portions thereof secured in aligned openings 14. A car 16 is provided for each of the cross rods 16. Each car 16 and the passengers thereof may be formed of a single sheet of relatively stiff light gauge material, such as paper which may be cut to form a body 17 of substantially rectangular form having extending portions at two opposite edges thereof fashioned to represent the upper portions of the bodies of miniature figures, as indicated at 18 in Figure 4. Slits are made in the ends of the body 17 adjacent to the corners of the body of the blank along the full lines indicated at 19 and the side and ends edge portions of the body then are folded upwardly along the longitudinal fold lines 20 and the transverse fold line 21, respec-

tively, thus producing a car having a bottom, sides, and ends and having upstanding projections on the sides of the car resembling portions of miniature figures. The slitting 5 of the ends of the body of the blank along the full lines 19 produces corner flaps at 22 when the marginal edge portions of the body of the blank are folded along the dotted lines 20 and 21 and these flaps 22 are folded 10 against the ends of the car and secured thereto by paste or other suitable means, whereby the ends and sides of the car will be stayed to each other and to the bottom of the car and will be held in place.

15 Each car is suspended, as by means of pairs of flexible suspension members 23 and eye members 24 from the associated rods 15 so that the car will remain in a horizontal position at all times. The suspension members 23 may be short lengths of thread which connect the ends of the eye members 24 with the upper edge portions of opposite vertical walls of the car.

A motor for operating the wheel on which 25 the cars 15 are supported may comprise a weight 25 and a cable 26 which is attached at one end to the weight 25. The cable 26 extends upwardly between one end member 8 of the wheel and the adjacent supporting 30 plate 6 and after being passed a plurality of times about the portion of the axle 7 which extends between said one end member 8 and the adjacent supporting plate 6 is secured to the axle. The weight 25 thus will be supported above the space within the upper section 3 of the supporting structure of the toy 35 when the wheel has been turned manually until a portion of the cable 26 has been wound on the axle 7 and the weight thus has 40 been raised above the level of the upper end of the box-like section 3.

A cone-shaped hopper 27 is supported in the space within the box-like upper section 3, by means of the suspension members 28 so 45 that the larger end of the hopper will be uppermost and in the path of downward movement of the weight 25 will extend centrally of the hopper 27 and the open smaller end of the hopper will be disposed directly above 50 and adjacent to the aligned openings 4 and 5 in the bottom of the upper section 3 and the top of the base section 1, respectively. The hopper 27 is adapted for the reception of sand or other granular material, such as indicated at 29 and the opening at the smaller 55 end of the hopper is of restricted area so that a considerable period of time will be required for all the granular material to pass by gravity from the hopper through the 60 aligned openings 4-5 into the space within the base section 1 after the hopper has been filled with sand or other suitable granular material.

From the foregoing description of the 65 various parts of the device, the operation

thereof may be readily understood. The box-like sections 1 and 3 of the supporting structure of the device, the supporting plates 6, the end members 8 of the wheel, the cars and the representations of passengers therein 70 as well as the cone-shaped hopper 27 may be made of pasteboard. The sleeve member 9 of the wheel may be a spool, the axle 7 may be a lead pencil, the cross rods 15 may be match sticks, and the suspension members 23, 75 26 and 28 may be lengths of thread or cord. A toy thus may be constructed of inexpensive materials which are readily available in practically all households. The weight 25 is placed on the mass of sand or other granular 80 material with which the hopper 27 has been filled and the weight will depend by gravity in the hopper as the granular material passes from the hopper into the chamber in the base section 1. The downward movement of the weight 25 of course will cause a torque to be imparted to the axle 7. The wheel thus will be rotated and the cars 16 will be carried in a circle about the axis of rotation of the wheel. The cars will remain horizontal 90 since the eye members 24 are free to turn on the supporting cross rods 15. A relatively short downward movement of the weight 25 thus will cause operation of the wheel for a 95 relatively long time.

Obviously, the invention is susceptible of embodiment in forms other than that which is illustrated in the accompanying drawings, and I therefore consider as my own all such modifications and adaptations thereof as fairly fall within the scope of the appended 100 claims.

I claim:

1. A toy comprising a rotary wheel, a gravity motor for operating said wheel, 105 said gravity motor including a vertically movable weight connected with said wheel, and means for regulating the downward movement of said weight, said regulating means comprising a receptacle in which said weight may move vertically, said receptacle having a discharge orifice at its lower end, and means movably supporting said weight within the receptacle and adapted to pass gradually from the receptacle through said discharge orifice, thus permitting downward movement of the weight in said receptacle, 110 said receptacle being substantially cone-shaped.

2. A toy comprising a rotary wheel, a gravity motor for operating said wheel, said gravity motor including a vertically movable weight connected with said wheel, and means for regulating the downward movement of said weight, said regulating means comprising a receptacle for a mass of granular material, said receptacle having a discharge orifice at its lower end through which the granular material will pass, and means supporting said receptacle in position to permit 115 120 125 130

the weight to rest on said granular material during the downward movement of the weight, said receptacle being substantially cone-shaped.

5. 3. In a toy of the character described, a wheel supported to rotate about a horizontal axis, a gravity motor including a weight connected to said wheel and adapted when moving downward to impart a torque to said wheel, and a cone-shaped hopper adapted for the reception of granular material and having an opening of restricted area at its lower end through which said granular material may pass by gravity, said hopper being supported in the path of downward movement of said weight so that said weight may rest on the granular material within the hopper and move downward in the hopper with the level of granular material in 20 said hopper.

4. A toy comprising a box-like base section, an upper section superimposed on the box-like base section and having an opening in its bottom in line with an opening in 25 the top of the base section, said upper box-like section being open at its upper end, supporting plates carried by two opposite walls of said upper section, a wheel supported to rotate between said supporting plates above the space within said upper box-like section, cars carried by the rim portions of said wheel, a gravity motor comprising a weight and cable connecting the weight with said wheel, a hopper supported 30 within the box-like upper section above the opening in the bottom of the latter, said hopper having a chamber therewithin taper-

ing in cross sectional area toward its lower end and having an opening of restricted area at its lower end from which granular material may pass and fall by gravity through the opening in the bottom of the box-like upper section into the box-like base section, the path of downward movement of said weight passing centrally of said hopper, 45 the top portion of said lower box-like section being removable.

5. A toy comprising a rotary wheel, a gravity motor for operating said wheel and including a vertically movable weight connected with the wheel, a receptacle in which said weight may move vertically, said receptacle having a discharge orifice of restricted area in its bottom and a fluid mass of substance in the path of downward movement of said weight in said receptacle and adapted to move gradually from position underneath the weight in the receptacle through said orifice thus permitting downward movement of the weight in the receptacle. 55

6. A toy comprising a rotary wheel, a gravity motor for operating said wheel and including a vertically movable weight connected with the wheel, a receptacle in which said weight may move vertically, said receptacle having an orifice of restricted area in its bottom and means within said receptacle including a fluid mass of substance adapted to pass gradually from the receptacle through said orifice for damping the downward movement of said weight. 70
